UNITED STATES PATENT OFFICE.

FERRIS SWARTWOUT, OF WESTERLO, NEW YORK.

CUTTER-BAR-LIFTING ATTACHMENT FOR MOWING-MACHINES.

SPECIFICATION forming part of Letters Patent No. 783,554, dated February 28, 1905.

Application filed August 3, 1903. Serial No. 168,067.

To all whom it may concern:

Be it known that I, FERRIS SWARTWOUT, a citizen of the United States, residing at Westerlo, county of Albany, and State of New York, have invented certain new and useful Improvements in Cutter-Bar-Lifting Attachments for Mowing-Machines, of which the following is a specification.

The invention relates to such improvements; and it consists of the novel construction and combination of parts hereinafter described and subsequently claimed.

Reference may be had to the accompanying drawings and the reference characters marked thereon, which form a part of this specification.

Similar characters refer to similar parts in both the figures of the drawings.

Figure 1 of the drawings is a view in perspective showing the improved cutter-bar-lifting mechanism applied to a well-known type of mowing-machine, the tongue being broken away and portions of the machine not directly connected with the present invention being represented by dotted lines. Fig. 2 is a diagrammatic view illustrating various positions which the cutter-bar can be made to assume by the use of this invention.

The object of the invention is to enable the operator of the machine to at all times control the position of the cutter-bar.

I have shown and will proceed to describe the invention in its application to what is commonly known as a "Deering Ideal" mowing-machine. In this machine the frame 1 is mounted upon a truck having traction-wheels 2, connected by the axle 3, adapted to be propelled by horses attached to the tongue 4, the operator occupying a seat 5. The drag-bar 6 is pivoted at 7 upon the frame 1 upon a horizontal axis, whereby the drag-bar is adapted to oscillate in a vertical plane, said bar occupying a more or less downwardly-inclined position in the normal operation of the machine. The cutter-bar 8 is swiveled upon or hinge-connected with the lower swinging end of the drag-bar at 22 through the inner shoe 9, to which the cutter-bar is fixed, the axis of the hinge connection being horizontal and at right angles to the cutter-bar and drag-bar.

10 is the pitman whereby the cutter-knives are actuated.

The parts above described are found in the type of mowing-machine above referred to, and their construction and manner of operation are well understood by those skilled in the art, so that further description of the general construction of the machine will be unnecessary for the purpose of the present invention.

In carrying out my invention in its preferred form I pivotally mount side by side upon the tongue at 12 a pair of foot-levers 13 and 14, each provided at its upper end with an outwardly-projecting foot-rest 15 and with an inwardly-projecting foot-rest 16, adapted to lap a similar inwardly-projecting foot-rest on the other lever, said inwardly-projecting foot-rests lying side by side and being adapted for simultaneous engagement by the same foot of the operator. The lever 13 on the right-hand side of the tongue can thus be conveniently operated by the right foot of the operator applied to the outwardly-projecting foot-rest 15 thereon. The lever 14 on the left-hand side of the tongue can be in like manner operated by the left foot of the operator applied to the outwardly-projecting foot-rest 15 thereon, while by the application of either foot to thelapping inwardly-projecting foot-rests 16 both levers can be simultaneously operated. The right-hand lever 13 is connected by a link 17 with one end of lever 18, fulcrumed at 19 upon the tongue forwardly of the foot-lever, the other end of the lever 18 being connected by a chain or cable 20 and the clip 21 directly with the drag-bar 6, embraced by said clip.

Separate operation of the foot-lever 13 will through the connecting mechanism described serve to lift the swinging end of the drag-bar and the inner end of the cutter-bar. It will be understood that the hinge connection 22 is so constructed that the cutter-bar is adapted to swing both upwardly and downwardly thereupon, so that when the hinge connection is lifted the inner end of the cutter-bar will be likewise lifted while its outer end remains resting upon the ground, whereby the cutter-bar is caused to assume a downwardly-inclined 100

position, which is desirable when passing a stone or other obstruction in the path of the inner end of the cutter-bar. The other foot-lever 14 is connected by link 23 with one end 5 of the lever 24, fulcrumed upon the tongue opposite and in the same manner as the lever 18, the other end of said lever 24 being connected with a rocker-arm 25, fixed upon the cutter-bar near its hinge connection with 10 the drag-bar, said connection being by means of a chain or cable 26, which passes from said rocker-arm around a pulley 27, rotatively mounted upon the clip 21, fixed on the drag-bar, and thence around pulley 28, mounted 15 upon the tongue, to the lever 24. The foot-lever 14 when separately operated thus serves to exert through the connecting mechanism a pull upon the rocker-arm 25, whereby the cutter-bar can be swung upwardly on its hinge 20 connection 22, causing said arm to assume an upwardly-inclined position desirable in passing a stone or other obstruction located in the path of the outer end thereof.

When both levers 13 and 14 are simultaneously operated by engagement of the operator's foot with both inwardly-projecting foot-rests 16, not only will the drag-bar and inner end of the cutter-bar and their hinge connection be elevated through the connections with 25 the lever 13, but the lever 14 will at the same time take up the slack which would otherwise be produced in the chain 26 as the roller 27 is raised with the drag-bar, whereby the chain 26 is held taut, preventing the cutter-bar from 30 swinging downwardly on its hinge connection, so that the cutter-bar will be raised bodily in a horizontal position, which is desirable in passing a stone or other obstruction located in the path of the middle thereof.

40 Reference to Fig. 2 will clearly illustrate the different movements of the cutter-bar above referred to. In said figure the cutter-bar is represented as resting horizontally upon the ground, 30 being the ground-line. In the 45 manner above described separate operation of the lever 13 will cause the cutter-bar to assume the position indicated by dotted lines 31, separate operation of the lever 14 will cause the cutter-bar to assume the position indicated 50 by dotted lines 32, and simultaneous operation of both levers 13 and 14 will cause the cutter-bar to assume the position indicated by dotted lines 33. The lifting-spring 34, connected at one end to the lever 24 and at the other end 55 to the frame of the machine, may be employed when desired to partly counterbalance the weight of the cutter-bar.

When desired, means may be provided for detachably holding the foot-levers 13 and 14 60 in a depressed position—as, for example, the hook 35, pivoted upon the tongue and adapted to engage either or both of the foot-rests 16 on the foot-levers.

An important object of my invention is to 65 enable the occupant of the seat of the machine

to control at all times during the operation of the machine the position of the cutter-bar. The foot-levers are located to adapt them to be engaged by the respective feet of the seat occupant, the seat affording a resisting support for the body of the operator, whereby he is enabled to use his feet while his hands are employed in manipulating the reins and operating the various hand-levers. By means of my improved construction the occupant of the 75 seat is enabled to instantly lift either the inner or outer end of the cutter-bar in passing over stones located in the path of such ends or to raise the bar bodily to pass a stone in the path of the middle of the bar, and this without interfering with his other duties in operating the machine.

The lever construction above described, comprising a pair of levers fulcrumed upon a common axis in close proximity to each 85 other, having mutually lapping operating members and each a separate unlapped operating member, may be employed in various situations where movements similar to those herein set forth are desired.

What I claim as new, and desire to secure by Letters Patent, is—

1. In a machine of the class described, the combination with the vertically - oscillatory drag-bar; and the cutter-bar hinge connected therewith to swing freely to a substantially unlimited degree both upwardly and downwardly from horizontal position; of a pair of foot-levers fulcrumed upon the frame of the machine adapted to be simultaneously engaged by the respective feet of the occupant of the machine-seat; mechanism connected with one of said levers and connected directly with the drag-bar whereby the latter may be elevated and supported by and under control of one 95 foot of the seat occupant at different elevations and whereby the inner end only of the cutter-bar may be lifted; and mechanism connecting the other of said levers with the cutter-bar whereby the latter may be swung upwardly on said hinge connection and supported by and under control of the seat occupant's other foot at various degrees of inclination, substantially as described.

2. In a machine of the class described, and in combination, the truck and pole; the vertically-oscillatory drag-bar; the cutter-bar; the hinge connection between the drag-bar and cutter-bar adapted to permit either end of the cutter-bar to assume a position above the plane of its other end; lifting mechanism connected directly with said drag-bar whereby the cutter-bar-connected end of the same can be elevated with said hinge connection above the plane of the outer end of the cutter-bar; a pulley mounted on the cutter-bar-connected end of the drag-bar; a pulley mounted upon said pole; a rocker-arm fixed upon said cutter-bar; a lever fulcrumed upon the frame of the machine adapted for operation either separately 110 115 120 125 130

or simultaneously with said lifting mechanism; and operating connections between said lever and rocker-arm consisting in part of a chain or cable passing around both of said pulleys.

- 5 3. In a machine of the class described, the combination with a cutter-bar; of a pair of foot-levers fulcrumed side by side, each having a foot-rest on its outer side, and having on the inner side mutually-lapping foot-rests 10 adapted for simultaneous engagement by the same foot; and connections whereby the outer end of the cutter-bar can be elevated by separate operation of one, and its inner end by 15 separate operation of the other, of said levers, and whereby the bar can be bodily elevated by simultaneous operation of both levers, substantially as described.

4. In a machine of the class described, the combination with a cutter-bar; of a pair of

foot-levers fulcrumed side by side, each having a foot-rest on its outer side, and having on the inner side mutually-lapping foot-rests 20 adapted for simultaneous engagement by the same foot; mechanism connected with one of said levers and connected directly with the 25 drag-bar whereby the latter can be elevated; a rocker-arm on the cutter-bar; a pulley mounted on the drag-bar; and mechanism connecting the other of said levers with said rocker-arm, consisting in part of a chain or cable 30 passing around said pulley, substantially as described.

In testimony whereof I have hereunto set my hand this 19th day of May, 1903.

FERRIS SWARTWOUT.
